UNITED STATES PATENT OFFICE.

MICHAL GORDON, OF BUFFALO, NEW YORK.

RAILROAD SIGNAL.

1,404,020.

Specification of Letters Patent. Patented Jan. 17, 1922.

Application filed June 15, 1920. Serial No. 389,172.

To all whom it may concern:

Be it known that I, MICHAL GORDON, a citizen of Poland, residing at Buffalo, in the county of Erie and State of New York, 5 have invented certain new and useful Improvements in Railroad Signals, of which the following is a specification.

The present invention relates to certain new and useful improvements in railroad 10 signals of that type embodying an audible alarm placed into operation upon the passing of the car wheels over and upon a trip positioned beside one of the tracks.

The principal object of the present invention is to provide an alarm of the above kind that is of such simple and durable construction as to meet with all of the requirements for a successful use with little 15 danger of getting out of order.

A further object of the invention is to provide a railroad signal embodying a casing carrying all of the operative parts of the signal and capable of being readily clamped against the side of a rail through 20 the use of the ordinary bolts used at the rail joint.

Other objects will appear as the nature 30 of the invention is better understood and the same consists in the novel form, combination and arrangement of parts hereinafter more fully described, shown in the accompanying drawing and claimed.

In the drawing forming a part of this 35 application and in which like designating characters refer to corresponding parts throughout the several views:—

Figure 1 is a fragmentary elevational view 40 showing a signal constructed in accordance with the present invention applied at a rail joint,

Figure 2 is an end elevational view thereof with the trip in its normal position,

Figure 3 is a view similar to Fig. 2, showing the trip depressed by a car wheel,

Figure 4 is a vertical sectional view taken 45 substantially upon line IV—IV of Fig. 2,

Figure 5 is a horizontal sectional view taken substantially upon line V—V of Fig. 1, and

Figure 6 is a vertical sectional view taken 50 substantially upon line VI—VI of Fig. 1.

Referring more in detail to the several views, the present invention embodies a preferably rectangular casing 5 whose rear wall 55 is provided with opposite hook-shaped ex-

tensions 6 adapted to rest upon and partially embrace the bolts 7 of the rail joint between the nuts 8 threaded on said bolt and the adjacent fish plate 9 whereby the casing is effectively rigidly secured in position beside the rail. The receptacle 5 is provided with hinged end doors 10 provided with suitable locks 11 which may be manipulated by an authorized person for obtaining access to the interior of the casing 60 when found necessary or desirable.

The top wall of the casing 5 is provided with a slot as at 12, adjacent the back of the casing, and a vertically slideable trip 13 is movable through the slot in a vertical direction and normally maintained upwardly in the path of the car wheel *a* by means of a helical compression spring 14 which is disposed within the casing with its lower end surrounding an upwardly projecting post 15, 70 which is rigid with the casing and its upper end surrounding a hammer or stud 16 which is rigid with and depends from a plate 17 secured to the enlarged base 18 of the trip 13. The enlarged base 18 provides an abutment for limiting the upper movement of the trip 13, and the plate 17 which is of electric conducting material is insulated from the base 18 by means of a rubber or 75 like strip 19.

The upper end of the post 15 is formed for reception of an explosive cap 20 adapted to be exploded by impact of the hammer 16 thereon upon depression of the trip 13 by the car wheel so as to provide a signal 90 of this kind when found necessary in place of the usual torpedoes in use at the present time.

Suitable spring strips 21 are provided upon the bottom of the casing 5 to form a 95 holder for the electric battery cells 22, it being the intention to employ one cell at a time and to have others at hand as shown in Figure 5 for being placed into immediate use upon expenditure of the electricity in the 100 battery already in use. As shown in Figures 4 and 5 one of the battery cells 22 is connected by a wire 23 to one terminal 24 of an electric bell 25 which is preferably rigidly fastened to the back wall of the casing 5 in 105 any suitable manner, and the other terminal 26 of the bell 25 is connected by a wire 27 to a spring strip contact 28. The contact 28 is fastened preferably as at 29, to the front wall of the casing 5, and extends rearwardly 110

in a horizontal position with its free rear end directly beneath a contact 30 provided upon one end of the plate 17. Another contact strip 31 similar to the strip 28 is fastened to the front wall of the casing 5 and has its free rear end disposed beneath another contact 32 provided on the other end of the plate 17, and this strip 31 is connected to the other pole of the battery cell 22 by a wire 33. It will thus be seen that when the trip 13 is depressed against the action of the spring 21, the plate 17 and its contacts 30 and 32 bridge the strips 28 and 31 so as to complete a circuit including the battery cell 22 and the bell 25 so that an alarm is sounded intermittently as the car wheels pass over said trip 13. Obviously, any one of the wires 23, 27, and 33 may be temporarily disconnected or a manually operable switch 20 may be provided in the circuit so as to render the electric alarm inoperative except when desired to be used as occasion may require. It will also be seen that by opening the doors 10, the battery cells may be renewed from time to time together with the explosive cap 20 or any other renewable or repair work may be accomplished with respect to the parts in the casing 5.

The front wall of the casing 5 is provided with numerous elongated slots 34 so as to permit the sound waves to leave the receptacle whereby the signal may be readily and

distinctly heard at some distance from the alarm.

It will thus be seen that the present device 35 embodies a portable self-contained alarm which may be readily applied for use and which is extremely simple in construction and efficient in operation.

From the foregoing description it is believed that the construction and operation as well as the advantages of the present invention will be readily understood by those skilled in the art.

Minor changes may be made without departing from the spirit and scope of the invention as claimed.

Having thus described my invention, what I claim as new and desire to secure by Letters Patent, is:—

A signal of the class described comprising a casing adapted for attachment to a railroad rail, a car wheel actuated trip projecting through the casing, spring means normally tending to project the trip from the 55 casing, an electric alarm circuit, contact points carried by the trip, and spring contact members bolted to the inside front wall of the casing and extending rearwardly therein adapted to underlie the contact 60 points of the trip for completing the electric alarm circuit when the said trip is depressed.

In testimony whereof I affix my signature.
MICHAL GORDON.
